POLARIZED DIRECTIONAL SIGNAL
SYSTEM

Clarence Palmer Stinson, Paola, Kans.

Application January 8, 1931, Serial No. 507,401

7 Claims. (Cl. 246—41)

The sketch shows only west-bound signals on a single track signalling system signalled for both directions of traffic. These signals are shown in the normal green proceed position. These 5 same signals would be opposing signals for an east bound train. An east bound train leaving the west siding would put all of these signals in the stop, red position to the east siding, giving 10 the east bound train protection from siding to siding. This same sketch turned around would give the east bound signals.

No. 3 signal is shown in the normal green position. Positive and negative battery current is flowing through front contacts 2 and 3 on pole 15 changing track relay 3 TR through front contacts 1 and 2 on relay 3 HD energizing relay 3 PC. Positive and negative battery current is flowing through polar contacts A and B and through front contacts 1 and 2 on relay 3 PC, positive battery 20 current is flowing through contact No. 1 of relays 2 and 5 TR energizing the approach relay 5 HD in the normal polarity to display a green proceed indication at signal No. 5. With the exception of No. 1 signal which is not embodied 25 in my invention all signals display a green proceed indication in the above manner.

No. 3 signal, we will say, is the second west-bound signal from the west siding. An eastbound train leaving the west siding will shunt out the 30 track circuit of track relay 1 TR, opening front contact 1 of relay 1 TR, which de-energizes relay 3 HD, thus opening front contacts 1, 2 and 3 of relay 3 HD; contact 3 on relay 3 HD drops on a back contact, making signal No. 3 display a red 35 light. Front contacts 1 and 2 opening on relay 3 HD, causes relay 3 PC to become de-energized; thus opening contacts 1 and 2 on relay 3 PC, which cuts off energy to the next signal relay 5 HD in the rear, which in turn causes all opposing 40 signals to be put to the red, stop position, in this manner, from siding to siding.

No. 5 signal, we will say, is the second west-bound signal from the east siding. Let us assume 45 a westbound train is approaching No. 5 signal, which is the normal green proceed position, the wheels of the engine pass west of insulating joints between relays 5 TR and 4 TR. This shunts the track circuit of relay 5 TR causing contacts 1, 2 and 3 on relay 5 TR to open; contact 1 opening on relay 5 TR de-energizes relay 5 HD; contacts 1, 2 and 3 of relay 5 HD open; contact 3 of relay 5 HD falls on back contact making signal No. 5 display a red light. Contacts 1 and 2 of relay 5 HD open and de- 50 energize relay 5 PC; a few seconds before contacts 1 and 2 of relay 5 HD open to de-energize relay 5 PC, the following takes place; relay 5 HD is a slow acting relay, and when contacts 2 and 3 open on relay 5 TR they fall on back pole changing contacts. This changes the wires positive 60 to negative, and negative to positive of current which passes through contacts 1 and 2 of relay 5 HD just a few seconds before contacts 1 and 2 of relay 5 HD opens, changing the polarity on relay 5 PC, thus resulting in reverse of the polar 65 contacts A and B of relay 5 PC. Relay 5 PC is now de-energized, and contacts 1 and 2 are open on relay 5 PC. The polar contacts through the 70 change of polarity on relay 5 PC are now making on polar contacts D and C. When the end of the train clears track circuit of relay 4 TR, battery current will flow through polar contacts D and C in the reverse polarity direction through relay 7 HD, which will display a yellow caution light at signal No. 7. When train passes into next block, 75 relay 5 HD will become energized in reverse polarity direction and signal No. 5 will display a yellow caution light. Relay 5 TR will be energized, and relay 5 PC will be energized to normal 80 polarity which in turn will cause polarity of current applied to relay 7 HD to display a green light at signal No. 7. The follow up or approach indications are accomplished in this manner.

I claim:

1. A single track railway signaling system 85 comprising, a single track section, successive signals for governing movements of trains through said section, a polar relay for governing each signal and governed in accordance with the position of contacts on a pole-changer relay at the 90 next signal in advance, said polar relay being energized at times by current of one polarity through polar and neutral contacts of such pole-changer relay at the next signal in advance, being energized by current of the reverse polarity 95 through polar contacts of said pole changer relay assuming the reverse position and irrespective of whether its neutral contacts are closed and being de-energized if the block between said first mentioned signal and said signal in advance is 100 occupied.

2. In combination, a stretch of railway track, signals located at intervals through the stretch for governing traffic in one direction and other signals located at intervals for governing traffic 105 in the opposite direction, a signal relay for controlling each signal, track circuits for the stretch including track relays for controlling said signal relays, means for controlling the signal relay for each signal by means at the next signal in ad- 110

vance governing traffic in the same direction as the signal relay governs and said means at the next signal in advance being responsive to the reversals of current for rendering the signal relay 5 for the signal next in the rear effective to display a stop, proceed or proceed with caution indication, means for controlling said last mentioned means by means of a pole changing track relay and a slow acting signal relay irrespective of the 10 corresponding signal.

3. In combination, a stretch of railway track, signals located at intervals through the stretch for governing traffic in one direction and other signals located at intervals for governing traffic 15 in the opposite direction, a signal relay for controlling each signal, track circuits for the stretch including track relays for controlling said signal relays, a polarized pole changing relay for controlling the position of each signal relay, by 20 means of the polar and front contacts of said polarized pole changing relay at the next signal in advance governing traffic in the same direction, means for controlling each polarized pole changing relay by a pole changing track relay 25 and a slow acting signal relay for the signal in advance, a normally closed energization circuit for each polarized pole changing relay each normal circuit including the two front contacts of a pole changing feature on a track relay and the 30 two front contacts of a slow acting signal control relay, a reverse circuit for each polarized pole changing relay including the two back contacts of same pole changing feature on track relay and the two front contacts on same signal 35 relay while signal relay is becoming de-energized but retains front contact pressure a length of time to change polarity on polarized pole changing relay, the said polarized pole changing relay when energized in the normal polarity rendering 40 the signal relay for the signal next in the rear effective to display a proceed indication and when de-energized in the reverse polarity rendering the signal relay for the signal next in the rear effective 45 to display a proceed with caution indication, and when de-energized in the normal polarity rendering the signal relay for the signal next in the rear effective to display a stop position.

4. In a railway signaling system, in combination: a stretch of single track divided into track 50 circuit sections, signals at intervals along the stretch for governing traffic in one direction, a polarized line relay for controlling the indications of each signal, a line circuit for each line relay extending to the signal next in advance 55 and controlled by the intervening track circuits, and means for controlling each line circuit for

the section in the rear by means of a polarized pole changing relay at the signal next in advance, said last mentioned means being controlled by means of a pole changing track relay and a slow acting signal relay for the said signal in advance

80

5. In combination two successive sections of a railway track, a signal located adjacent the entrance end of each section, a signal relay for each signal for the control thereof, a line circuit for each signal relay extending to the signal in advance, track circuits for the sections including track relays for controlling the line circuits of the signal relays, means for controlling the line circuit for the section in the rear by means of a polarized pole changing relay at the signal in advance, the said polarized pole changing relay being controlled by means of a slow acting signal relay and a pole changing feature on the track relay for said signal in advance, a normally closed energization circuit for each polarized pole changing relay, each normal circuit including the two front contacts of a pole changing feature on the track relay and the two front contacts of the signal control relay, a reverse circuit for each polarized pole changing relay including the two 100 back contacts of same pole changing feature on track relay and the two front contacts on same signal relay while signal relay is becoming de-energized but retains front contact pressure a length of time to change polarity on polarized 105 pole changing relay.

90

6. In combination, a stretch of railway track, signals located at intervals in said stretch for governing traffic in one direction, a signal circuit for each signal, means for controlling each signal circuit by means of a polarized pole changing relay at the signal next in advance and means dependent on the direction of traffic to reverse said polarized relay by train movement in one direction of traffic and not in the other direction.

110

7. In a railway signaling system, in combination: a stretch of track divided into track circuit sections, signals located at intervals along the stretch governing traffic in one direction, a line relay and a polar relay associated with each such signal, line circuits for the line relays, each line circuit being controlled alternatively by the polar and front contacts of the normally energized polar relay for the next signal in advance 125 or the reverse polar contacts only of the said polar relay, when said polar relay is deenergized and means for controlling the polarity of the polar relays selectively for only one direction of traffic.

CERTIFICATE OF CORRECTION.

Patent No. 1,952,826.

March 27, 1934.

CLARENCE PALMER STINSON.

It is hereby certified that error appears in the printed specification of the above numbered patent requiring correction as follows: Page 1, before line 1, insert:

The invention relates to improvements in railway signaling, which I call Polarized Directional and is to be used on railroads where traffic is in both directions on the same piece of track.

When a train leaves one siding, all opposing signals are automatically put in the stop position to the next siding; on the approach or followup move, a train can follow a signal block behind another train.

And that the said Letters Patent should be read with this correction therein that the same may conform to the record of the case in the Patent Office.

Signed and sealed this 19th day of June, A. D. 1934.

Bryan M. Battey
